UNITED STATES PATENT OFFICE.

EDWARD E. CLEMENT, OF WASHINGTON, DISTRICT OF COLUMBIA, ASSIGNOR, BY
MESNE ASSIGNMENTS, TO FREDERICK C. STEVENS, OF ~~ATLANTA~~, NEW YORK,

TELEPHONE-EXCHANGE SYSTEM

1,107,143.

Specification of Letters Patent. Patented Aug. 11, 1914.

Application filed March 15, 1906. Serial No. 306,292.

To all whom it may concern:

Be it known that I, EDWARD E. CLEMENT, a citizen of the United States, residing at Washington, in the District of Columbia, have invented certain new and useful Improvements in Telephone-Exchange Systems, of which the following is a specification, reference being had therein to the accompanying drawing.

10 My invention relates to telephone exchange systems, and has for its object the improvement of such systems in point of efficiency and economy. In order to attain this object I employ a combination of apparatus, a portion of which is manipulated by operators, and other portions are automatic in their action.

Briefly stated, my present invention comprises the following elements: Subscribers' 20 stations equipped merely with telephone talking and signal-receiving sets, of the ordinary or any desired type used in manual systems; line-circuits connecting these substations and a central office and there carried to what I shall call my relay-primary-selector sets, being multiplied into a number of these sets; dummy trunks terminating each in a relay primary selector set, and adapted to be connected automatically there- 30 by to a subscriber's line when calling; automatic switches less in number than the number of lines, a set of these switches being connected to each dummy trunk; a signal impulse generator common to all the apparatus; operators' signaling keys associated with the dummy trunks adapted to connect the impulse generator thereto; and finally multiple-contacts for the subscribers' lines in the banks of the automatic connector 40 switches.

Stated in similarly brief terms, the operation of this system is as follows: Assuming the subscribers to be supplied with current from a common battery at the central office, a subscriber calls by removing his receiver from the hook in the usual manner, thereby energizing certain of the primary selector relays of his set, which in operating automatically connect his line to an idle dummy trunk and set a signal before the operator to whom that trunk belongs. The operator may have a listening key, or may be automatically connected to this trunk when the signal is set, and she thereupon ascertains 50 from the subscriber the number wanted.

She then sets her signaling keys or buttons in accordance with said number, thereby connecting the main impulse generator to the automatic switches, so as to send a proper succession of impulses to operate the 60 switches to select the line wanted, and to test and ring the same. I make the operator's keys preferably mere push-buttons fitted with latches, and arranged in sets of ten. The operator's work is thus reduced to getting the number and pressing the proper buttons.

The underlying principles of which I have made use in this invention sufficiently appear from the foregoing statement, and will 70 be claimed broadly in their application. The amount of detail involved in a system of this character, all of which it is necessary to explain in order to make a complete disclosure, is so great that there is of course 75 some danger of appearing to limit the invention to specific arrangements which in fact may be varied without changing the principles involved. It is to be understood that for the sake of clearness I shall make 80 the following detailed description absolutely specific, but do not mean to limit myself thereby to such specific disclosure only.

My invention is illustrated in the accompanying drawings, in which— 85

Figures 1 to 8, inclusive, constitute when put together a continuous diagram of one complete embodiment of my invention. Of these, Fig. 1 shows the subscribers' stations and lines. Figs. 2, 3 and 4 show portions 90 of three primary selector sets; Fig. 5 shows three trunks, and operating relays, with three different arrangements, Fig. 5^a two others. Fig. 5^b shows three trunks all having a uniform arrangement, similar to that 95 of the upper trunk in Fig. 5. Fig. 6 shows a set of signaling buttons and an impulse generator therefor to work with Figs. 5 or 5^a. Figs. 7 and 8 show the automatic switch circuits; Figs. 9 and 10 are respectively a 100 side and top plan view of a ten point relay used in my system; Fig. 11 is a front view, and Fig. 11^a is a bottom plan view of a typical automatic switch which may be employed, and which is illustrated for descriptive purposes only; Fig. 12 is a condensed diagram of a primary selector set; Fig. 13 is a diagram of a modified arrangement of sending buttons and impulse generator, similar to that shown in Fig. 6; and Fig. 14 110

shows a modified arrangement of trunk circuits to coöperate therewith. Fig. 15 is a diagram of a secondary selector set governed by the trunk relays, for automatically connecting the operators to trunks.

Before proceeding to the circuits, where-in the invention in the present case resides, it will be advisable to obtain a clear understanding of the types of apparatus which I employ, and which are shown in Figs. 9 to 11^a, inclusive. I do not give any special illustration of a single point or ordinary relay, for the reason that everyone skilled in the art is so familiar with these devices as to render it unnecessary. That portion of my system which is illustrated in Figs. 2, 3 and 4 constitutes what I have termed the primary selector or answering portion of the system. In this appear a number of ten point relays and a number of single point or ordinary relays. These latter may be of any suitable type. The only special feature required is that of double winding, which, as I shall point out hereinafter, can be dispensed with if some other means be provided for locking the relays when energized. The apparatus at the subscribers' stations also forms no part in itself of my present invention, except as it co-acts with the apparatus and circuits at the central office. I contemplate using an ordinary common battery telephone outfit the same as those employed in standard manual switchboard systems.

Referring then to Figs. 9 and 10, I will briefly describe the ten point relay, N. This comprises an iron back yoke, n , a pair of magnets, n' , mounted thereon, an armature, n^2 , extending across the front end thereof, and a set of contact-springs, n^3 , n^4 , n^5 , n^6 , overlying the upper bell-crank extension of the armature, so as to be worked thereby. There are eleven sets of these springs, all secured at the rear end of the relay upon the return portion, n^7 , of the back yoke. The front ends or pole pieces of the cores of the electro-magnets, n' , receive the front yoke, n^8 , of non-magnetic material, such as brass, this also having an upper return portion, n^9 , overlying the magnet windings, and alined with the return portion, n^7 , of the back yoke, n . Upon this return portion, n^9 , of the front yoke the upper bell-crank arm, n^{12} , of the armature, n^2 , lies flat under normal conditions. Cut from end to end of this upper bell-crank portion, n^{12} , are two grooves in which rest the insulating studs of the spring sets. The function of these slots with the studs resting in them is to retain the armature in place. At their front ends the springs are separated by shouldered studs, the lowermost stud of each pair resting upon the armature, carrying the lower spring of its pair, n^8 , on its shoulder, and the upper spring, n^5 , on its head, its

stem passing through a hole in the spring, n^6 , while the uppermost stud of each pair rests upon the spring, n^5 , supports the spring, n^4 , upon its shoulder, and carries the spring, n^3 , on its head, its stem passing through a hole in the spring, n^4 . The actuating studs affect only the springs, n^4 , n^6 , of each set, these constituting the movable springs, while the others, n^3 , n^5 , are fixed. Each actuating stud carries the spring, n^6 , on its shoulder, and the spring, n^4 , on its head, its stem passing through holes in the springs, n^5 , n^6 .

The entire relay is secured to an insulating back block, n^{10} , by means of the bolts, n^{11} , constituting extensions of the cores and threaded to receive lock-nuts. The rear ends of the contact-springs extend out through openings made in this block, and an inclosing shell or casing, n^{13} , is fitted to the block, with which it forms a tight joint all around the edge. This shell is secured in place by means of the stud, n^{14} , threaded to receive the nuts, n^{15} . As the armature, n^2 , is attracted, the springs, n^4 , n^6 , are lifted by the actuating stud, until their outer points make contact with the corresponding points of the springs, n^3 , n^5 , in each set. Ten of these sets are line-contacts, and the eleventh is for locking purposes, as will sufficiently appear from the description of the circuits.

Referring now to Figs. 11 and 11^a, I have therein shown a piece of apparatus which I do not present as a part of my invention, nor as an example of finished design in an automatic switch, but which is typical of the class of switches commonly known as "Strowger" or "automatic electric" switches. As I have previously pointed out, my present invention may be practised with various connecting means, but in order to render this description complete and coherent, I include this form of switch and its circuits.

As illustrated in Figs. 11 and 11^a the switch is designated *in toto* by the letter S, and represents a selector switch, that is one of the intermediate switch units to transfer a connection from the calling line to an idle trunk and switch in the desired thousands or hundreds group. It has a frame, s , provided with two posts, s' , extending downwardly to support the contact-banks, s^2 , s^3 , which as shown in Fig. 11^a are arranged in an arc-shaped figure around the central spindle, s^4 . There are ten rows in each contact-bank, with ten pairs of contacts in each row of the bank, s^2 , and ten single contacts in each row of the bank, s^3 . The contacts are radial strips of brass or German silver clamped solidly between upper and lower plates, s^5 , and separated by suitable insulation. Upon the spindle are mounted the wipers, s^6 , s^7 , s^8 , the latter being a connected pair adapted to rub against both faces of

the single contacts in the banks, s^8 , and the former being separate wipers adapted to rub upon opposite faces of the pairs of contacts in the bank, s^2 . Connection is established with these wiper springs through a flexible cord or similar means, which I have not deemed it necessary to show.

The spindle, s^4 , is a long straight piece of steel, journaled in the upper and lower members of the frame, s , so that it can both turn and slide therein. Its own weight normally keeps it down in the position shown in Fig. 11, with the wipers out of alignment with any of the contacts. The parts are not drawn to scale, but it is supposed that the first upward step of the spindle produced in the operation of the vertical magnet will bring the wipers opposite the respective first rows of contacts in the banks, and each successive step upward will shift the wipers opposite another row. After being stepped up until the wipers are opposite the desired rows, the spindle is then supposed to be turned one step at a time by the rotary magnet until the wipers rest upon the contacts of an idle trunk. For the purpose of effecting these vertical and rotary movements, the spindle carries two ratchets, s^9 , s^{10} , the former having a number of annular teeth, usually eleven or twelve, and the latter having a circular series of vertical straight teeth, which usually do not extend entirely around the ratchet surface, but only far enough to carry the arc through which the wipers must sweep when passing over all the contacts in a row. The vertical movement of the spindle is effected by the magnet, w , and the rotary movement by the magnet, r , both being mounted on the frame. The magnet, w , has an armature, w' , drawn down by a spring, w^2 , and carrying a pivoted pawl, w^3 , provided with a tail spring, w^4 , which tends to throw the tip of the pawl into engagement with the ratchet, s^9 , but is normally prevented from doing so by the stop pin, w^6 , set in the back plate, s^11 , which is supposed to cover the entire back part of the frame, s . When the magnet, w , is energized it draws up its armature, w' , and the point of the pawl, w^3 , is immediately thrown forward to engage the upper tooth of the ratchet, s^9 , the continued upward motion of the armature then raising the spindle and its wipers one step. The rotary magnet, r , has an armature, r' , appearing edgewise to the observer, in Fig. 11, and pivoted at its nearest edge in a vertical line, so that the edge away from the observer swings to and from the magnet poles, moving the extended arm, r^2 , back and forth, and by means of the terminal pawl, r^3 , turning the ratchet, s^{10} , the pawl normally being retracted by the spring, r^4 .

In order to retain the spindle in any position to which it may be raised and turned

by the magnets, w , and r , I provide a pair of swinging pawls, t' , t^2 , whose ends engage the respective ratchets, s^{10} and s^9 , and whose bell-crank body, t^3 , is pivoted between posts, t^4 , t^5 , at the edge farthest from the observer. 70 Upon the front edge of the body is a projecting pin, t^6 , adapted to be engaged by the link, t^7 , on the upper end of the armature lever, t^8 , of the release magnet t . The link and the lever are normally drawn over 75 by the spring, t^9 , into the position shown in Fig. 11. The pawls t' , t^2 , are normally held in engagement with their respective ratchets by a suitable spring, not shown. When the magnet, t , is energized it draws 80 over the lower end of the armature lever, t^8 , to the right, throws the link, t^7 , to the left until it passes over and engages the pin, t^6 , and when the magnet is again deenergized the spring, t^9 , again draws the link to the 85 right and swings the bell-crank body, t^3 , upon its pivots so as to raise the pawls, t' , t^2 , from their ratchets and permit the spindle to be rotated so as to disengage the wipers, s^6 , s^7 , s^8 , from the rows of contacts and then 90 to drop into the normal position of disuse. These are the operating members of the switch. In addition, the switch frame carries an escapement and its controlling magnet for the side switch and for certain contacts which will be specified in the description of the circuits. The side switch is shown in front view in Fig. 11, at u . It consists of a plurality of switch-arms mounted one over the other with interposed insulation, the entire set being carried upon a lever, u' , pivoted at u^2 , and normally held in the position shown, against the tension of the spring, u^3 , by the engagement of the upper end, u^4 , with the first one of a number of 95 teeth, u^5 , carried upon the armature lever u^6 , and constituting an escapement. Whenever the magnet, U , is energized the lever, u^6 , is thrown over to the left, the tip, u^4 , passing 100 a fractional step to the right. When the armature is again retracted the tip passes a full step to the right, and so on, these steps placing the arms, u , successively in contact with the first, second and third sets of fixed contact points, u^7 , on an insulating block 105 carried by the frame. When the switch spindle is all the way down in its normal position the lower edge of the ratchet wheel, s^{10} , engages the short upper arm of the bell-crank lever, u^8 , whose lower arm engages the 110 lever, u' , to push the same back into initial position as shown in the figure.

The magnet, U , at certain times has its armature mechanically held up, and for this purpose a projecting finger, u^9 , is attached 115 to the armature, r' , of the rotary magnet, r . Upon the upper part of this finger a button of insulating material is placed to engage and normally keep closed a pair of contacts, u^8 , in the circuit of the magnet, r . 120

130

These contacts and the projecting finger r^5 , are used only in the selector switch, in which the rotary movement is accomplished by constant and automatic vibrations of the armature r' , until an idle trunk is found by the wipers. The magnet, U, controls a set of contact springs u^8 , u^9 , the former normally closed, and the latter normally open. When the armature, u^9 , is attracted the conditions 10 of these springs are reversed.

In order to restore the spindle to its normal position in a rotary direction, a coiled spring is provided housed in a cap s^{12} , at the top of the spindle, one end of the spring 15 being attached to the same, and the other end to a lever arm, s^{13} , loosely journaled at one end on the spindle between the cap and the collar, s^{14} , and loosely sliding at the other end on a post, s^{15} . The collar, s^{14} , carries the stop arm, s^{16} , which abuts against a turned down leaf on the arm, s^{13} , when the parts are in normal position, the tension of the spring thus being carried by a pressure 20 of the arm s^{14} upon the turned down leaf 25 on the arm s^{13} and the arm s^{13} surrounding the post s^{15} , thus being relieved of any rotational pressure against the post s^{15} and being thus placed in position to slide vertically upon the post s^{15} with little or no friction. 30 The travel of the arm, s^{13} , up and down the fixed post, s^{15} , and the vertical extension of the ratchet, s^{10} , enable the spindle to be turned and restored through its full sweep when in any previously assumed vertical position. 35

Having thus described the mechanical parts a knowledge of which is essential to the comprehension of my circuits. I turn to the description of the latter, beginning 40 with Fig. 1. Therein I have shown three subscribers' stations, A, A', A², each equipped with a telephone transmitter, a receiver, a switch-hook, a ringer, and condenser, all of usual or suitable type for use with common battery circuits. When the hook is up, that is when it is relieved of the weight of the receiver, the circuit is through the transmitter and receiver; and when the hook is down, the line-circuit is completed for alternating current only, through the ringer and condenser. Since the circuits are the same for all the lines, I will refer to the line 45 from station A only. This consists of conductors 1 and 2, extending from the substation to the central office. At the substation the talking circuit is completed through the wires 3—4 when the hook is up, and the ringing circuit through the wires 5—6 when the hook is down. These figures 50 are useful for the purpose of tracing the circuits only.

Turning now to Fig. 2, the line-wires 1 and 2 appear at the left hand side of the figure, terminating in contacts of the cut-off 55 relays, M', which are normally deenergized,

so that in each case the line-wire 2 is grounded at 7 and the line-wire 1 extended through line 8 to the line-relay M, and so to main battery B and ground. The armature, m, of each line-relay M is grounded at 9, 70 and when attracted is adapted to close upon terminal contacts of wires leading to the tens and units relays of the primary selector sets. I preferably divide all the incoming lines in an exchange into groups of say one 75 hundred each, and to each group I apportion a fixed number of trunks leading to connective apparatus. In a small or comparatively inactive exchange the percentage of these trunks may be as low as five, and 80 in busy exchanges it may be raised to ten or even fifteen. I assume, however, that ten per cent. of connective apparatus will be sufficient to care for the present system, hence I provide ten trunks for each one hundred lines, and a complete set of tens and units relays in a primary selector group for each trunk. The circuits herein illustrated show six lines, which for convenience I will call Nos. 500, 501 and 502 (Fig. 2) and 90 510, 511 and 512 (Fig. 3). The subscribers' circuits of Fig. 1 will fit any of these, and in order to fully comprehend the connections of these lines and the arrangement of the tens and units relays, it is necessary to consider Figs. 2, 3 and 4 together. In Figs. 2 and 3 the subscribers' extension lines are shown coming into their initial terminals on the tens relays, which are of the type shown 95 in Figs. 9 and 10. Each of these relays carries the terminals of ten lines, and for each trunk there are ten of these relays, so that for 100 lines, provided with ten trunks, there will be 100 ten point relays, containing 1,000 line-terminals; from which it appears that 105 each line can be multiplied ten times, which it should be in order to obtain access on occasion to every one of the ten trunks. The contacts on the ten point relays are arranged 110 in duplicate pairs. That is, the incoming 110 lines terminate each on one pair of springs, opposite which another pair of springs appears to which the line is connected when the relay is energized, and from which a local circuit passes to the front contact 115 springs of a particular units relay or single point relay. For each group of ten tens relays there are ten units relays, or twenty relays in all for each trunk. A group of this kind constituting one primary selector or 120 dummy trunk terminal for thirty lines, is shown in Fig. 12, apart from the other figures, so as to free the lines from their multiple connections. In order to make clear 125 the connection of a line coming into the exchange, I will first refer to this figure and then trace the circuits through the others.

In Fig. 12, N, N', N², are three relays of the type shown in Figs. 9 and 10, having ten pairs of contacts each for the line-circuits. 130

These relays correspond to the relays shown in Figs. 2 and 3, correspondingly lettered. At the top of the figure I have shown the terminal ends of lines 500 to 529, inclusive, 5 connected to a pair of contacts, n^3 , n^5 , such as shown in the mechanical figures 9 and 10. For lines 500 to 509 these terminals are in the relay N. For lines 510 to 519 they are in the relay N'. For lines 520 to 529 they 10 are in the relay N². Thus each relay contains line-terminals, n^3 , n^5 , for ten lines. When any one of the lines appropriated to a particular relay is calling, the electromagnet, n' , of that relay becomes energized. 15 This will be explained in connection with the circuits of Figs. 1 and 2 farther on. For example, if any line from 500 to 509 originates a call, the magnet, n' , of the relay, N, will become energized, and simultaneously 20 connect all of the lines from 500 to 509 onto the extensions 10 to 19, inclusive. If, however, the calling line is in the group from 510 to 519, the magnet, n' , of the relay, N', will become energized, connecting all that 25 group onto the extensions 10 to 19, inclusive. Similarly, if the calling line be in the third group, from 520 to 529, the magnet, n^2 , of the relay N² will be energized, connecting that entire group onto the extensions 10 to 30 19, inclusive. Thus extensions 10 to 19 are seen to be common to all of the tens relays, and in fact each extension pair is multiplied to corresponding contacts in all of the tens 35 relays. No. 10 extension goes to the first pair of contacts, n^4 , n^6 , in each of the relays, N, N', N². Extension No. 11 is multiplied to the second pair of contacts, n^4 , n^6 , in each of the relays, and so on with all the 40 extensions up to No. 19.

At the lower edge of Fig. 12, I have shown ten units relays, marked P to P⁹, inclusive. These are the same as the relays in Fig. 4, similarly marked. Each is a simple standard relay, of the type in common use, and 45 preferably of the same general type as that shown in Figs. 9 and 10, hereof, viz., that type in which the electromagnet is mounted horizontally on a frame or rack, carrying the contact springs upon it, and the whole is 50 inclosed within a dust-proof shell. Each relay has an armature, p^2 , adapted to be actuated by an electromagnet, p' , to close together the contacts, p^3 , p^4 , and p^5 , p^6 . In the present instance, that is in the trunk 55 group of each primary selector, all of the contacts, p^5 , p^6 of the entire set of relays, P to P⁹, are connected in a set of double parallel branches marked 20 to 29, inclusive, which are really so many bridges across the 60 trunk circuit, 30—31.

The outfit shown in Fig. 12 is sufficient for 30 lines, and by its use any one of the lines, 500 to 529, may connect itself to the trunk 30—31, by merely closing its line- 65 circuit, and energizing the appropriate

tens and units relays. The energizing circuits are not shown in Fig. 12, but will be described in connection with Figs. 2, 3 and 4. They comprise parallel branches closed by the line-relay of each line when calling, one 70 branch going to the appropriate tens relay, and the other branch going to the appropriate units relay, which thus becomes energized simultaneously and act in conjunction to connect that particular line and no other 75 to the trunk. For example, suppose line No. 512 is calling, the subscriber having taken down his receiver from the hook, so as to close his line-circuit as shown in Fig. 1, and energize his line-relay, M, shown in Fig. 80 3. This line-relay closes two branches, one leading to the tens relay, N', in Fig. 12, and the other leading to the units relay, P², which is the third in the set of ten. The actuation of the tens relay, N', connects all 85 of the lines 510 to 519 onto the extensions ten to nineteen, inclusive; but it will be observed that these extensions are open everywhere else, hence no effect is produced by this action alone. The third units relay, P², however, connects the third extension 12 to the trunk 30—31, through the branch 22, and by following the circuits in Fig. 12 90 it will be found that this connects the line 512 onto the trunk direct, whereupon the trunk relays become energized, and further proceedings may be had. Only one line is thus connected to the trunk at a time, assuming of course that only one tens relay and one units relay of the same set be 95 energized simultaneously. It is true that the tens relay connects all of its lines onto the extensions; but all of these extensions are open except the particular one which is 100 closed onto the trunk by the particular units relay energized. It is also true that the extension thus connected to the trunk is multiplied to the corresponding pair of contacts in everyone of the tens relays, but this produces no effect, because all but one of the 105 tens relays remain deenergized. Before passing from Fig. 12 it is necessary to call attention to the fact that only three tens relays are there shown, accommodating 110 thirty lines. This limitation is due to the necessary limitations of a Patent Office drawing, and it is to be understood that the same principles apply to any desired group up to 100 or more. It is most convenient in 115 a scheme like this to make use of the decimal system, using ten relays per trunk, ten lines per relay, and ten trunk multiples per line. For 100 lines there would be ten of the tens relays, N, N', N², etc., but still only ten of the units relays, and each of the extensions 120 10 to 19, inclusive, instead of being multiplied three times, would be multiplied ten times, into all the tens relays.

Turning now to Figs. 2, 3 and 4 we have 125 here the same relays described in connection 130

with Fig. 12, but somewhat differently arranged. Only two tens relays and three units relays of each set or of each trunk are shown. I have assumed the numbers 500, 501 and 502 for the lines entering Fig. 2, and 510, 511 and 512 for the lines entering Fig. 3. The first three lines being within the same tens digits of each other go onto the same tens relays in each set. For the sake 10 of convenience I have given the designating numerals of the relays coefficients, and have marked the three trunks in Figs. 4 and 5 so as to be readily followed. Thus in Fig. 2 all three of the lines come into the relay N, 15 which is adapted to put them onto the extensions, 10, 11, 12, etc., leading to the units relays, P, P', P², etc., in Fig. 4. (I should here remark that the tens relays in Figs. 2 and 3 are not shown with their full comple- 20 ments of springs, for the sake of simplicity. Each of them is supposed to have ten pairs of contacts, in accordance with the showing of Figs. 9, 10 and 12). Each of the lines 500, 501 and 502 not only terminates in contacts 25 of the relay, N, but is multiplied to similar contacts in the relays 1N, 2N, etc. There would be one of these added for each trunk, that is appropriated to the group of lines. In the present case I only illustrate three 30 trunks, so that each line need be multiplied only three times.

In Fig. 3, the lines 510, 511 and 512 are connected to the tens relays, N', 1N' and 2N' in the same manner as the lines in Fig. 35 2, each line being multiplied three times so that each may have access to any one of the three trunks. It will be understood of course that the relays, N, N', of Figs. 2 and 3, and P, P', P², of Fig. 4, constitute one 40 set, appropriated to the trunk 30—31, and have precisely the same relation among themselves and the same connections, as the set shown in Fig. 12. Similarly the relays 1N, 1N', 1P, 1P', 1P² all belong to one set, 45 appropriated to the trunk-line 130—131. Similarly again, the relays 2N, 2N', 2P, 2P' and 2P² belong to one set, appropriated to the trunk-line 230—231. The extension 50 from the tens relays to the units are marked 10, 11, 12 for the first set, 110, 111 and 112 for the second set, and 210, 211 and 212 for the third set. As these of course bear a logical relation throughout, and follow the same arrangement as that in Fig. 12, it is 55 thought no difficulty will be experienced in comprehending the meaning of Figs. 2, 3 and 4. If Fig. 12 is understood, the description of the other figures may be put into one sentence. They show several 60 groups like Fig. 12, with the line-wires multiplied to each group instead of terminating as in Fig. 12 in single pairs of contacts. The actual connections controlled by the relays N and P being thus understood, it is 65 most important to explain the means by

which I control these relays. Referring to Fig. 2, the line-wires 1 and 2 terminate as I have stated, in the contacts of the cut-off relay M', through which they are normally connected to the line-relay M and 70 ground. When the subscriber at station A takes the telephone receiver from the hook, he closes his line-circuit, the line-relay M is energized, and the two branch circuits 50 and 51 are immediately closed. The branch 75 50 passes in multiple to one winding of each of the three tens relays, N, 1N and 2N, these relays being double-wound for the purpose of making them self-locking when attracted. Any one of these relays might thus be en- 80 ergized by any one of the three lines shown, but it is my purpose that only one of them shall be so energized at once, and that no two lines shall be able to energize the same relay at the same time. Hence, on the other 85 side of these relays I take away the circuit-wires, which are designated generically by the numerals 54, 55 and 56, to three separate controlling means in the shape of special relays associated with the switch trunks. 90 Each of these first named relays has its locking coil open on one side, but adapted to be grounded by the relay itself in pulling up; and on the other side of this second or locking winding it is connected through 95 one of the wires indicated by 57, 58 or 59, to controlling means similar to those I have just mentioned and which will also be specified later. The second branch from the line relay is marked 51 for line 502; 52 for line 100 501; and 53 for line 500. In other words, each of these lines has its own units wire, as will be apparent at once if Fig. 12 has been understood. The three wires, 51, 52 and 53, pass along the bottom of Figs. 2 105 and 3 and into Fig. 4, where they terminate in the first or operating windings of the three relays, P, P', and P², also by multiples in the corresponding windings of the relays, 1P, 1P', 1P² and 2P, 2P', and 2P². The three 110 relays, P, P' and P², since they belong to the same set, have a common control, their return wires (of the set 54) marked 54^e, 54^f and 54^g, passing to contacts in a twenty-pair relay D^x, see Fig. 5. This relay controls 115 the return wires of both the tens and units relays of this set, twenty in all. I find it advisable to have a relay provided with separate terminal contacts for each of the wires 54^e, 54^f, etc., in each set 54, 55 or 56, because 120 of certain complications which arise when battery is put on without any resistance, the working then being on a margin which is too narrow to be called absolute. In other words, when the controlling relay for any 125 set has cut off the return wires from the actuating windings of the tens and units relays, they are all separated from each other and as those of one trunk only are closest together at any one time, the separa- 130

tion of the relays associated with the other trunks prevents the formation of any parallel paths when the line calls. The relays D^x , $1D^x$ and $2D^x$, associated respectively with the trunks 30—31, 130—131 and 230—231, are respectively controlled by the relays D' , $1D'$ and $2D'$. An inspection of Fig. 5 will show that when one of the latter relays pulls up current is placed on the relay of the set D^x , $1D^x$ of the succeeding trunk thereby rendering the trunk in condition to receive the next call. The relays of the set D' , $1D'$ and $2D'$ may therefore be termed pilot relays since they prepare a succeeding trunk for receiving the next call.

Each of the units relays in Fig. 4 has a locking winding separated from the actuating winding and each locking winding terminates on one side in a contact normally open but adapted to be grounded when the relay is energized. All the locking windings of the first set or group have a common return, 61, passing onto the wire 57, which is the control wire of the locking windings on the tens relays, N , N' . This wire 57 passes into Fig. 5 and is there carried to a pair of the trunk relays by which it is controlled, being preferably open except when the trunk is in use, and at such time being connected to battery. The actuating windings of the units relays, $1P$, $1P'$, and $1P^2$, have return wires generically indicated by the numerals 55, (and individually as 55°, 55^f, etc.), passing to the contacts of the relay $1D^x$ associated with trunk 130—131. The locking windings of these relays have a common return 63, which goes to the wire 58, passing into Fig. 5 and there controlled by one of the trunk relays in the same manner as in the first set. Similarly, the actuating and locking windings respectively, of the units relays, $2P$, $2P'$ and $2P^2$, have their return wires passing into Fig. 5 and there controlled by relays associated with trunk 230—231. It is thought the scheme will now be plain. Suppose that one of the line-relays as that of line No. 502, pulls up. It grounds the local circuits 50 and 51 and energizes whichever one of the tens relays, N , $1N$ or $2N$ happens to be idle, together with the appropriate units relay. This would be one of the three relays, P^2 , $1P^2$, or $2P^2$ in Fig. 4. The selection of the tens relay for energization depends upon two conditions; first, the relay selected must be idle and available for service and, second, of all idle relays it must be the one which alone stands eligible for service by reason of precedence controlling devices constituted by the armatures of relays D' , $1D'$ and $2D'$ of Fig. 5 and which will be described in due course. The tens relay and units relay thus selected having pulled up, their locking windings are grounded, and hence they are maintained energized through the locking common re-

turn as long as a subscriber keeps his receiver off the hook, being finally deprived of current when the subscriber hangs up, so that the relays are then restored. The circuit over which the selected tens relay is energized may be traced as follows: beginning at battery B in Fig. 5, thence through the armature contacts of relay $2D^x$ to conductor 56^a, passing through Figs. 4 and 3 into Fig. 2 where it passes through the energizing winding of relay $2N$, conductor 50, through contact and armature of relay M, conductor 9, and returns through the earth to battery B. The circuit over which the units relay is energized may be traced as follows: beginning with battery B in Fig. 5, thence passing through armature contacts of relay $2D^x$ and to the actuating winding of relay $2P^2$ through conductor 51 downward and to the left through Figs. 4 and 3 and into Fig. 2, thence on conductor 51 through contact and armature of relay M and conductor 9, and returning through earth to battery B. I have thus shown, first, a single trunk group of primary selector relays, and second three such groups, or at least portions of three groups, belonging to three several trunks, and having the subscribers' lines connected to them in multiple. I will now point out how a calling line is permitted to select an idle trunk only, by working idle relays only. For this purpose it is necessary that I should refer briefly to Fig. 5. This figure shows portions of three trunk-circuits, each of which commences at the letter x on the left of the figure, which is supposed to be the terminal point of attachment of the selective set shown in the preceding figures and in Fig. 12. The three trunks are marked, respectively, 30—31; 130—131 and 230—231. Each of them is divided by condensers, C, so that the portions to the right of the condensers in the figure can be used for sending direct current out through the switches without interfering with the incoming call end. I have designated the outgoing or switching end of the trunk as 30°—31^f, etc. Across the incoming or answering end of each trunk is bridged a pair of relays, D , D' , $1D$, $1D'$ or $2D$, $2D'$, each with the main battery, B, between them. This battery is grounded as usual on its positive terminal, and when the primary selector set first puts a call on one of the trunks, as 30—31, its sleeve relay, D' , will immediately pull up in series with the cut-off relay of the calling line. The incoming end of the trunk, therefore, corresponds to the answering cord of a cord-circuit of an ordinary manual system, the primary selector set performing the same functions as the plug and jack; hence, the battery supply for talking as well as for signaling over the calling line is drawn through two relays, D , D' , D' being the 130

sleeve relay, remains energized as long as the primary selector set is on, which is the same as saying as long as the answering plug is in the answering jack of the calling line. 5 The relay, D, on the other hand responds to the subscriber's acts, being energized by current coming over the subscriber's line, and therefore is controlled by his switch-hook. It will be observed in the switching end of 10 the three trunks shown in this Fig. 5, that in each instance there is a starting relay, E^s, which is normally deenergized, but becomes energized when the starting impulse comes over the starting wire 84. I run the 15 common return wire, 57, or 59 from the locking windings of all the primary selector relays of each trunk preferably to a back contact on a starting relay, E^s, this contact being closed upon main battery B, when the 20 trunk is in use. I run the locking wire 58 of the middle trunk to a back contact on the relay, E^s, which is in this case merely an extra relay controlled by the relay, E^s, and put in in order to relieve the latter of some 25 of its contacts. These relays are all energized when the switching is done, but they serve normally to keep current on the locking wires, so that when any set of relays pulls up it will be enabled to lock instantly, 30 even before the tip relay, D_t, of the trunk has pulled up. When this latter relay becomes energized, it assumes control of the locking wire in every case, and since the signaling relays are all locked up during a connection, the relay, D, alone controls the locking 35 windings, and releases the same to clear out when the calling subscriber hangs up his telephone.

Having thus shown that the locking windings are all maintained active, it remains 40 to point out how the actuating windings of the different selective relay sets are rendered active one at a time. This is by means of the relays, D' D^x. In Figs. 5 and 45 14 it is assumed that the lowermost trunk is No. 1, the next above is No. 2 and the uppermost trunk, 30—31 is No. 3, in the order of their becoming busy. The instant a call comes in and is put on the lower trunk, 50 230—231, its sleeve relay, 2D' is pulled up and puts battery on the relay, 2D^x. This latter relay is normally deenergized, and the actuating windings of the various tens and units relays belonging to its trunk are therefore normally closed onto battery through the 55 wires 56^a, 56^b, 56^c, 56^d, 56^e, etc.; there being twenty relays to the trunk and hence twenty wires for the actuating windings, I employ a ten-pair relay of the type shown in Figs. 60 9 and 10, at the point, 2D^x. Of course the springs on this relay may be arranged to either open or close the respective circuits when the relay is energized, as the case may be. The relay 2D^x of the first trunk must 65 open these circuits. Succeeding relays must

leave them normally open and when energized must close them. In other words, the relay selector of the first or lowermost trunk is in condition to get current at once and hence will take the first call. As soon as 70 this call is placed on the trunk, the relay 2D' puts battery on the wire 14 leading to the armature of the relay 1D' of the next trunk, which normally completes the circuit of the relay 1D^x. The latter becoming energized 75 immediately closes battery onto the actuating windings of the relay primary selector set of its trunk, which thereupon becomes sensitive and in condition to take the next call; and so on to succeeding trunks. 80 But the line relay of the line calling and taking the trunk 230—231 is deenergized by the energization of the cut-off relay of that line in series with the relay 2D'; thus the grounds at the line relay are removed 85 before the second trunk is placed in commission by the energization of the relay 1D^x, and action in trunk 130—131 may not be effected by the calling line which has taken trunk 230—231. I have shown only 90 five contacts on each of the controlling relays, for the sake of simplicity in illustration, but it will be understood that there may be as many as are required.

Further details of the trunk arrangements 95 will appear from the statement of operation. The modifications shown in Fig. 5^a are in the relays E^s, E^s, E^s, the sleeve and tip relays of each trunk being in themselves the same in every case. The only requirement 100 is that the locking wires 57, 58 and 59 must be normally held on battery by some of the trunk relays which will become energized when a connection is completed, so as to leave control thereafter to the tip relay, D. 105

Figs. 6 and 13 show what I shall call a multiple number transmitter, which is common to all the operators in the exchange, or to any desired group. This signal transmitter, which is really an impulse generator 110 or commutating device, is constantly driven, and according to present practice in such matters it will be installed in duplicate, at least; so that no mishap to one machine can stop the entire work of the exchange, 115 which would result if there were only one machine and it should get out of order. The preferred arrangement of this transmitter is seen in Fig. 6. Herein I show a set of wheels, Q', Q², Q³, Q⁴ and Q⁵, provided 120 with 1, 2, 3, 4 and 5 teeth, respectively. A complete machine will have ten of these wheels, so that any digit from 1 to 10 can be indicated by sending the appropriate number of impulses. In the drawing, in order 125 to economize space I show only the first five wheels. In practice these wheels are all one, the teeth being formed upon the surface of a drum which is driven by a suitable motor at constant speed. The speed which I have 130

found most suitable for this device and for the type of switches I here illustrate, is approximately twelve revolutions per minute. Each wheel is provided with four spring 5 contact-pens, q^1 , q^2 , q^3 and q^4 , through which the impulses are transmitted to the four sets of keys, K' , K^2 , K^3 and K^4 , in the order of the numbers. The pen, q^1 , of the wheel, Q' , is connected to the individual spring, 71, 10 of key, k' , in the set, K' , by means of the wire, 72. Similarly, the pen, q^1 , of the wheel, Q^2 , is connected to the spring, 73, of the key, k^2 , of the set, K' , by the wire 74, and so on; the succeeding wires being marked 15 75, 76, and 77, all of which go to the individual springs of the keys of the set, K' . The second set of springs, q^2 , are connected in the same order to the individual springs of the keys, belonging to the set, K^2 ; the 20 third set of springs, q^3 , are similarly connected to the individual springs of the key set, K^3 ; and finally, the fourth set of springs, q^4 , are connected to the individual springs of the four keys, K^4 . The layout 25 in this figure is intended for an exchange of 1,000 lines or less (assuming the circuits to be extended to ten wheels), the three sets of keys, K' , K^2 and K^3 serving to send impulses from three sets of number-wheels for 30 selective purposes, while the fourth set of keys, K^4 , is intended in the present case for selective ringing on party-lines. The first wheel, Q' , is shown as fitted with an extra set of five pens, q^5 , q^6 , q^7 , q^8 and q^9 , and a 35 projecting pin, q^{10} . The pin, q^{10} , and pens q^5 , q^6 , q^7 , q^8 and q^9 might be fitted upon a separate wheel, but for convenience I have shown them thus adapted to the first number-wheel. In practice, of course extra teeth can be 40 located on the drum wherever desired. The pens, q^8 and q^9 I shall refer to as the stopping and the starting pens, respectively, and each of them forms the terminal of circuit through which control of the apparatus is 45 effected in a manner I will point out later. The starting circuit is marked 84 and the stopping circuit 85. Extending parallel to these circuits is the wire 86, which carries the controlling or so-called "rotary" 50 impulses from the pens, q^5 , q^6 , and q^7 , which are tied together so that all are in connection with the wire 86. Three impulses are thus thrown upon the wire 86 for each revolution, and the pin, q^{10} , is so placed with respect to the tooth on the wheel, Q' , that it touches the two pens, q^8 , and q^9 in succession just before the tooth of the wheel, or the first tooth on any of the other wheels comes into contact with the first pen of its set, or 55 immediately after the last contact of the numerical teeth of any wheel with pen q^1 of that wheel, the true requirement of the setting of the pin q^{10} and the pens q^8 , q^9 being that the contacts of the pin with the 60 pens occur between successive cycles of con-

tacts of the number teeth of the wheels with the pens of the respective wheels.

The key set, K' , is provided with bus-bars or common springs, 78, all connected together and to the wire 79; the keys, K^2 , have 70 similar common springs connected to the wire 80; the keys, K^3 , have similar common springs connected to the wire 81; and finally the keys, K^4 , have similar common springs connected to the wire 82. The four wires 75 79, 80, 81 and 82 are all joined together and connected to the common wire 83, which carries to the switches in proper sequence the vertical actuating impulses. The wheels, (or the drum) Q' , Q^2 , etc., are all electrically 80 connected together and to the main battery, B. This may be a special battery, but I have found it unnecessary to do any more than take current off the main battery bus in the exchange. Each set of keys, K' , K^2 , K^3 , 85 and K^4 is provided with a common latch-plate, such as shown for instance in Patent to Ham, No. 634,575, and others; the purpose of this plate being two-fold. It prevents more than one key being depressed at 90 a time, since such depression of a key forces back the plate and releases any key which had previously been depressed; and it also holds down the key last depressed, thereby keeping the circuit closed through which ever wire was selected. Thus, suppose it be desired to transmit over the wire 83 the number 433-3. The operator depresses the fourth key in the first set, the third key in the second set, the third key in the third set, 95 and finally the third key in the fourth set. Thus, the spring, q^1 , of the wheel, Q^4 , becomes connected through wires 76 and 79 to the wire 83; the spring, q^2 , of the wheel, Q^3 , becomes connected through its wire to the 100 wire 80 and so to the wire 83; the spring, q^3 , of the wheel, Q^2 , becomes connected through its wire to the wire 81 and so to the wire 83; and finally the spring, q^4 of wheel, Q^3 , becomes connected through its wire 88 to the 105 wire 82 and so to the wire 83. Now, as the drum or the wheels rotate, what happens is this: first, one impulse from the wire 84, then four impulses over the wire 83 from the wheel Q^4 , then a single impulse over the 110 wire 86 from the pen, q^5 , then three impulses over the wire 83 from the wheel, Q^3 , then another single impulse over the wire 86 from the pen, q^6 , then three impulses over the wire 83 from the wheel, Q^2 , then another single 115 impulse over the wire 86 from the pen, q^7 , then three impulses over the wire, 83, through the ringing key set, K^4 , from the wheel, Q^3 , and finally an impulse through the stopping wire 85 from the pen, q^8 , when 120 the complete signal as required has been transmitted. Any one familiar with the operation of the Strowger system of switches will at once perceive that the wires 83 and 125 86 can be connected directly to the vertical 130

and the rotary side of a switch trunk, respectively, and the impulses will then serve to operate the switches perfectly; and I may here state that the sole function of the starting and stopping wires 84 and 85 is to connect and disconnect the sending device to and from such a trunk at the beginning and end of a complete rotation or signal sequence. Obviously, if the operator set up the signal 10 at the keys, K' , K^2 , etc., and the impulses were then permitted to go directly into the switch circuits, great confusion would result, for the reason that the connection might be made in the middle of a rotation, and the 15 numbers sent would then utterly fail to correspond with those selected. By using a starting device actuated only at the commencement of a rotation, however, and connecting this to a wire 84 which is available 20 for the circuits of all the operators, it is possible to set up any signal in any position, and all signals will be commenced at the right place, that is at the beginning. Similarly, the connection must be broken after the 25 proper sequence of numbers has been sent, or a further succession or rotation of numbers would be transmitted, which would be undesirable and might interfere with the proper ringing or other operation. The 30 circuits of Fig. 6, thus described, are particularly adapted to coöperate with the trunk circuits shown in Fig. 5. The apparatus for the incoming end of each trunk has already 35 been described, and part of the controlling apparatus, in so far as it is related to the first-named; but I will now point out all the apparatus of these trunks, in order to make 40 clear the connection with Fig. 6.

As already stated, three trunks are shown 45 in Fig. 5, and each one is different in its arrangement, the purpose being to show how this sending device of Fig. 6 may be adapted to different forms of trunk. The upper trunk in Fig. 5 has four controlling 50 relays, an operator's listening key, O , and what I shall call a "starting" button, E^k , which when depressed is held down by an electromagnet after the fashion of the keys shown in Letters Patent No. 672,122, April 55 16, 1901, to W. W. Dean. In this case the operator sets up the number wanted on the key sets, K' , K^2 , etc., and then depresses the starting button, E^k , which is held down until the signal has been transmitted in a 60 manner which will presently be pointed out. The middle trunk in Fig. 5 also has four controlling relays, a listening key, O , and a starting key, E^{40} ; the last-named in this case being a master-key with a mechanical 65 latch controlled by an electromagnet in the stopping circuit. In brief, the operation of this trunk is such that the operator sets up the number wanted on the keys, K' , K^2 , etc., then depresses the starting button, E^{40} , and the latter is latched, closing the circuit of a

starting relay which responds to the starting impulse to connect the wires 83 and 86 onto the switch trunk. At the end of the revolution of the common sender or drum in Fig. 6, the impulse over the stopping wire 85 trips the latch of the starting button, and restores the same, thereby cutting off the signaling wires 83 and 86 and completing the trunk for conversation. The third trunk at the bottom of Fig. 5 has three controlling relays, and a starting relay, E^4 , which serves the same purpose as the key, E^k or E^{40} , in either of the other trunks, the electromagnet controlling the key, E^{40} , responding in this instance to the temporary closure of a controlling circuit, which may be at the extra springs shown in the key set, K^4 , in Fig. 6, if desired. In such case, the device is set ready for operation as soon as the operator has depressed the last key indicating the number wanted. I do not consider this procedure as satisfactory as the other, for the reason that an operator may and even will by accident depress the wrong key in one of the sets, K' , K^2 , etc., becoming conscious of the mistake at the instant of making it. Under such circumstances, if the number selected is not put on the wire or set up until a starting button is pressed, the operator is enabled to correct her error by depressing the proper keys; but on the other hand if the signal is set as soon as the selective keys are depressed, then there is no opportunity for correction without perhaps mutilating the signal. In this third trunk of Fig. 5, I have shown the starting and stopping wires, as well as two springs from the key set, K^4 , in order to illustrate a modification of this mechanism and the circuits thereof. If this is employed, the corresponding parts of Fig. 6 will of course be omitted. Further details of the arrangement will appear fully from the statement of operation hereinafter. Referring now to modifications in Figs. 110 13, and 14, the latter shows three trunks which are all alike. The arrangement of the sleeve and tip relays, and the relays, D^x , is precisely the same as in Fig. 5. The functions and arrangements of the relays, D^2 , 115 D^3 , etc., is different, however, and will be briefly described. The locking wire 57 comes into a front contact of the relay, D , and also to a back contact of a relay, D' , the armature of which is connected directly to the main battery. The purpose of this is to positively supply battery current to the locking wire until the relay, D , shall have time to pull up. The sleeve relay, D' , of course pulls up first when a line comes on a 120 trunk, taking current through the line-cut-off relay, M' . (See Fig. 2). This closes the circuit of the lamp, L , through a back contact of the relay, D^3 , the lamp glowing to signal the operator that a call is on the 130

trunk. When the listening key, O , is depressed by the operator, the actuating circuit of the relay, D^3 , is closed, and the relay pulls up, thereby breaking the lamp circuit, and connecting the companion relay, D^2 , to battery. The relay, D^3 , locks itself up, through the front contact of the relay, D' . D' , D^3 and D^2 thus constitute successive elements in a chain which becomes energized and deenergized in step-by-step order. The purpose of introducing this chain of relays is to insure the proper transmission of the releasing impulses to both sides of the trunk when the calling subscriber hangs up at the close of a conversation. At such time the relay, D , is the first to fall back, closing the battery wire through its back contacts and the front contacts of the relay, D^2 , to both sides of the trunk. The relay, D' , is next to fall back, releasing and followed by relay, D^3 , which in turn releases and is followed by the relay, D^2 , which cuts off the release wires from the trunk. In this Fig. 14, the wires 83 and 86 are shown coming into the trunks direct, the controlling relays being entirely separate from the trunk relays and being shown in Fig. 13. In Fig. 14 three trunk equipments are shown, each having conductors 83-86. In Fig. 13, the conductors 83-86 are shown leading to contacts of a pair of relays. Each trunk of Fig. 14 has an individual pair of relays per Fig. 13 and also a set of keys per Fig. 13 individual to the trunk, the commutator wheels and pens of Fig. 13 however being common to a plurality of trunks and may be to all of the trunks in the central office. In Fig. 13, the wheels, Q' to Q^5 , are arranged and connected substantially the same as in Fig. 6, all being joined together and connected to battery, while their four sets of pens are connected in the same manner to the respective sets of keys, K' , K^2 , K^3 and K^4 , which however are shown in reversed order. In addition to the number-wheels a separate controller wheel, Q^{11} and a rotary impulse wheel, Q^{12} , are provided. The starting and stopping wheel, Q^{11} , is shown with an insulating tooth coöperating with the two pens, the starting and stopping wires passing respectively to contacts on the relays, E^2 , E^3 . The wheel, Q^{11} , itself is connected to battery. This wheel conveys current to both the controlling wires, 84 and 85, the former of which passes through a front contact on relay, E^2 , to battery, and also to the locking armature of E^3 , the result being that as long as the relay, E^2 , is energized the relay, E^3 , will remain locked regardless of the condition of wire 84. The wire 85 on the other hand, comes direct to the locking armature of relay, E^2 , hence this relay is absolutely dependent for continuation of energization upon the condition of wire 85. The impulse wires 83 and 86 pass

through back contacts of the relay, E^2 , and front contacts of the relay, E^3 ; hence in order that impulses may be transmitted to the trunk circuits of Fig. 14, it is necessary that the relay, E^2 , should be deenergized 70 and the relay, E^3 , be energized. They are always operated in this order, by means of the wheel, Q^{11} , with its insulating tooth, which traveling in the direction of the arrow always momentarily breaks circuit 75 through the wire 84 first, and then through the wire 85. When the operator, having set up the number wanted, depresses the ringing button, K^4 , a circuit is closed from the main battery wire 89 through the branches 90, 91 80 and 92 to the relays E^2 , E^3 , both of which are thus energized, and both of which promptly lock themselves through the wires 84 and 85, deriving their current supply thereafter from the wheel, Q^{11} . I should 85 here state that in this Fig. 13 the keys, K' , K^2 , K^3 and K^4 are supposed to be what are known as three-position keys; that is if a button is pushed down from its normal retracted position it latches in a middle position so as to make the desired selective connection; and if pushed down farther to the limit of its movement it will make another connection, which however is broken when the key is retracted once more to the middle 95 position. Such keys are commonly employed for selective ringing.

As the wheels or drum revolve in Fig. 13, the insulating tooth on Q^{11} may pass under the spring terminal of the wire 84, without 100 effect, since the relay, E^2 , remains locked and so guards the other at the contact, e^{20} . Just before the first tooth reaches any spring, g' , however, the insulating tooth comes under the terminal pen of the wire 105 85, which for a moment loses current, thereby permitting the relay, E^2 to become deenergized. Its armatures in falling back complete the circuit of the wires 83 and 86, and all the impulses of the signal numbers for which the keys K' K^2 K^3 K^4 have been set go in in their order, while the relay, E^3 , remains energized. At the end of a full rotation, however, when the insulating tooth again comes under the terminal pen of the wire 84, the relay, E^3 , becomes deenergized at once, since its companion is no longer able to guard it. Hence both relays being off, the wires 83 and 86 are disconnected until the next operation of the keys.

I will now briefly describe the switching mechanism shown in Figs. 7 and 8. Fig. 7 shows a first selector switch, S , and a second selector switch, S' , while Fig. 8 shows a connector switch, S^2 . All three of these 125 switches are of the type shown in Figs. 11 and 11^a, and I will not go into any detailed description, leaving the functions to appear from the statement of operation. In each case I have shown the various magnets and 130

relays marked the same as in Figs. 11 and 11^a. Turning in particular to Fig. 8, there is added to the ordinary switch connector mechanism a four-party selective automatic ringing device. The vertical relay, V, in a ground tap from the trunk wire 38, controls the vertical and rotary magnets, *v* and *r*, and also the ringing, as shown. Up to the point of operating the ringing relay, when the side switch-arms are on their last contacts, there is nothing unusual about the circuits. When the line wanted has been selected, however, tested, and the trunk connected by the side switch-arm 1^u, 2^u, 3^u and 4^u, passing to their last points, instead of an ordinary ringing relay, *w*, being placed directly under control of the vertical relay, V, I place what I call a ringing control relay, *w'*, at the disposal of the vertical relay, V, through the wires 43, 44, 45, 46, 47, 48 and 49. This relay, *w'*, then works the bank of generator selecting relays, and finally gives control of the ringing to a commutator, Y, which is common to the entire exchange or all the switches, and which puts on and takes off ringing current in any desired manner and for any desired period. The relay, *w'*, has its armature on battery, and its front and back contacts connected through wires 68 and 69 to the armatures of a pair of relays, *w*⁴ and *w*⁵, which are normally deenergized. The relay, *w*⁵, is the first one of a set of three which control the connection of the frequency generators, G, G', G², G³, to the tip ringing wire, 106, all the generators being on a common return 107, which goes to the sleeve side of the ringing key. The usual connection to battery is made through a resistance, in order to hold up the cut-off relay during ringing. With all the relays, *w*⁵, *w*⁷ and *w*⁹ deenergized, the first generator, G, is connected to the wire 106 through the wires 115, 114, 113, 109, 108 and 106. When relay, *w*⁵, becomes energized, the generator, G, is cut off, and the second generator, G', is cut on, the wire 116 being substituted for 115. If the relay, *w*⁷, be energized, the third generator, G², is cut on, wire 117 being substituted for the wire 114, and so on. Obviously, I am not limited to three relays nor to four generators, being able to use in fact as many generators or as many connections in their place for selective ringing, as I may desire. Present commercial practice, however, only calls for four parties on any one line, and I therefore show generators which may advantageously deliver current at 16, 33, 66, and 100 cycles, respectively. The subscribers' ringers on the same line will then have their armatures tuned to respond to the respective currents, and no grounds will be required.

The relays of the first set, *w*⁵, etc., could not for various reasons be positively oper-

ated in succession by themselves. In order to give this positive operation I provide a second set of guard relays, *w*⁴, *w*⁶ and *w*⁸. The wire 69 is normally open at relay, *w*⁴, but the first impulse through the relay, *w*⁷, puts battery on the wire, 68, which pulls up the relay, *w*⁴, and so closes the wire, 69 through the wires 91, 99 onto the relay, *w*⁵. When the wire 69 is again closed, battery passes to the relay, *w*⁶, and the first generator is exchanged for the second, wire 116 being substituted for 115, the relay at the same time locking itself on wire 101, and also connecting the wire 68 through the wires 92 and 97 to the next 80 guard relay, *w*⁸. If no further impulse comes matters remain this way, and it will be observed that if no impulse had come at all, the first generator would have remained undisturbed. This first generator, therefore, 85 is the one that I employ for all single party-lines, since the operator does not need to press a ringing key at all, but merely sets up the number of a line. In Fig. 6 to be sure, I have shown four keys in the set, K¹, 90 but these may well be reduced to three, the first station on the line being automatically rung by the machine without the operator doing anything. Hence the preferred arrangement in practice is to have four sets 95 of ten keys each, in order to send the whole number of the line wanted up to 10,000; then have three selective ringing keys marked we will say "d", "h", "m", and colored green, white and red. One station 100 on each party-line, and every station on a single line, will therefore be automatically rung without selection by the operator, who will merely set up the number of the line. For a "d", "h", "m" party, however, the 105 operator will depress the proper button in addition.

In order that the ringing current may not go out upon the called line, while the relay set, W, is being worked for selective purposes, I provide a slow acting relay, *w*², in the shape of a solenoid, which pulls up quickly, but takes a perceptible time to fall back. This relay is tapped off between the battery wire 67 and the control wire 48, in 115 a path, 66, in parallel with that of the relay, *w*⁷. At the first impulse it pulls up and opens the commutator wire 119, or the generator wire 106, 109, or as I have illustrated, it may open both of them. When the selective impulses have ceased, the solenoid lets its core fall all the way down, and the wires 119, 106—109, are then completed, so that ringing can proceed. In order that the sleeve relay, X', may hold up, during ringing, I provide a ground tap through a suitable resistance, *y*, which is put on in place of the cut-off relay when the ringing relay, *w*, operates. Otherwise, the relay X' would lose current. According to the arrange- 130

ment shown the relay, w , will continue to operate at intervals as determined by the commutator, Y , ringing the called subscriber, until the latter answers. When he answers, he thereby closes his line-circuit through his telephone, and in the next interval of non-ringing, the relay, X , will take current, and break the battery connection of the wire 101, thereby cutting off the ringing relay, so that the commutator will not be able to reach it to put it on again. In order that when the conversation is concluded the called subscriber may not be rung back to his phone, I provide the locking relay, w^3 , which also controls the circuit 119, 120, and which takes current through the wire 103 when the relay, X , is energized, locking itself through wire 102, which depends upon the relay, X' , and that 20 in turn upon the usual sleeve connections. Hence when the switch is released by its release magnet, t , at the end of a communication, all the relays, X , X' and W are off. I should observe that the locking wire 101 25 passes under control of the relay, X , so that the relays, W of the selective set are restored as soon as the called subscriber answers. They may, however, be held up over the same locking wire 102 as the relay, w^3 .

I will now briefly recapitulate the operation of my system, tracing a complete connection from the first call to the final disconnect. For this purpose I will use Figs. 1, 2, 3, 4, 5, 6, 7 and 8, assuming that subscriber A in Fig. 1 calls for subscriber A³, in Fig. 8. When A takes down his receiver, his line circuit 1—2 is closed, the line relay 2M pulls up, (and assuming that all connective apparatus is idle) the relays, 2N and 2P in Figs. 2 and 4 pull up, their return wires, 56^a and 56^b being normally closed through the contacts of the relay 2D^x in Fig. 5. The extension wires from the cut-off relay, 2M', are thus prolonged by way of contacts 500 and wires 210 to the trunk 230—231 in Fig. 4, and so to the same wires in Fig. 5. Current immediately flows from the main battery B in Fig. 5 through the sleeve relay, 2D', and back through the sleeve side of the trunk to the cut-off relay, 2M' and to ground, the cut-off relay thereupon immediately pulls up, putting the subscriber's line onto the extensions and so onto the trunk, whereupon the tip relay 2D of the trunk pulls up. This closes battery from wire 14 to the locking wire 59, the same being temporarily maintained through back contact of relay, E³. The relays 2N and 2P remain locked 55 therefore, subject to the control of the relay 2D, which is controlled by the subscriber, A. When the relay 2D' pulls up, putting battery on the wire 14, it energizes the relay 2D^x, which pulls up and cuts off all the 60 turn wires 56^a, 56^b, etc., of the selector relays,

2N, 2P, etc., of its set. The trunk is thus disabled for any other calls. At the same time current passes through the wire 14 to the armature of the relay 1D', of the next trunk, through a back contact thereof and so to the 70 relay 1D^x, which pulls up and puts battery on the actuating windings of the relays in 1N, 1P, etc., of its set. Battery on the wire 14 accomplishes another thing, passing to a pair of normally closed contacts of relay, 75 E⁵, and so through wire 18 to the signal lamp, L, which immediately lights, announcing a call. The operator then depresses her listening key, O, and inquires the number wanted.

Although I have shown in Fig. 7 a first selector switch, it will be observed that in Figs. 6 and 13 I only show three sets of number buttons, the fourth being employed for selective ringing. The buttons, therefore, 80 are only sufficient in number for a one thousand line exchange, in which I should not employ first selector switches, the second selectors and connectors being sufficient. For the moment, therefore, it will be understood 85 that the switch, S, merely remains quiescent on the first contact, or is cut out entirely, the trunk 30^x—31^x going directly to the wires 34, 35 of the second selector switch. All that is required in order to use the first 90 selector and go up to ten thousand is the addition of another set of keys in Fig. 5; in order to go to one hundred thousand still another set would be employed. For each additional set of keys an additional set of 100 springs, q , q' , etc., must be provided. Assuming the number wanted in the present case to be 433-3, the operator depresses the fourth key in the set, K'; the third key in each of the sets K², K³ and the third key in 105 the set K⁴. It is supposed we are employing the lowest trunk in Fig. 5, and it will be observed I have shown a pair of spring-contacts marked K^x. It will also be observed that I have shown some open contacts 110 on the set, K⁴, in Fig. 6. The reason for these features in illustration is that the contacts thus marked are the starting contacts, that is they put the signal when set up, in condition to be started by the machine. 115 may either be attached to the last set of number-keys, K⁴, or they may be separate as shown at K^x in Fig. 5. As previously stated, I prefer the latter construction. Having set up the number, the operator 120 closes one of the keys, K^x, and thereupon puts battery on the starting relay, E⁴, by the following path: B, 7, K^x, E⁴, and ground. The relay, E⁴, thereupon pulls up 125 and locks itself on a branch circuit through the resistance r_h . It will be observed that the full voltage of the battery is put on the relay to pull it up, and the current through this resistance is only required to hold it up, which it is well able to do. The relay, 130

E⁴, being energized, presses down its three long springs, the upper pair severing the trunk, and connecting the forward ends 230^x and 231^x onto contacts leading through wires 128 and 129 to the front contacts of relay E⁵. The lowest spring 133 connects the starting wire 84 with the wire 134 leading to a winding of relay E⁵. This terminates the work of the operator. She pays no further attention whatever to this connection, but turns to other things. The machine in Fig. 6 being constantly driven, the pin, q¹⁰, finally reaches the spring, q⁹, and sends an impulse through the starting wire 84. This reaches the relay, E⁵, and that relay becoming energized immediately connects the wires 83 and 86 to the wires 128 and 129 and thence to the forward ends of the trunk; it also locks itself on the wire 14, being thenceforth under control of the relay, 2D'. It also breaks the circuit 14—18 of the signal lamp, L, which goes out, thus indicating that the signaling has commenced. It also takes the battery off its branch of the locking wire 59, leaving the subsequent control of that wire to the relay, 2D. It also connects a shunting wire 126 to the stopping wire 85, whose pen, q⁸, in the present instance is momentarily grounded at the end of a signal. Conditions being as thus stated, the wire 83 remains connected to the tip side of the trunk 230^x, for one complete cycle of the wheels in Fig. 6; and wire 86 remains connected to the sleeve side 231^x of the same trunk during the same period. The impulses over the sets of pens corresponding to keys K'—K², K³—K⁴ will therefore be transmitted in succession over the wire 230^x, with a single intervening impulse over the wire 231^x to separate succeeding groups. At the end of one rotation of the main sender wheels, the pin or stud on the wheel, Q^x (which is a grounded wheel separate from the others in Fig. 6) gets around to the spring, q⁸, and by touching it puts a dead ground on the wires 85 and 126, and hence short-circuits the magnet, E⁴. This magnet having a considerable load on it immediately lets go, permitting its long springs 135 and 136 to assume their uppermost position against the trunk springs 137, 138, thereby cutting off all connection with the wires 83, 86, 128, 129 and completing the trunk circuit for conversation, clean and clear.

The foregoing is the operation with the form of trunk shown at the bottom of Fig. 5. The next trunk in order has two relays, E⁵, F⁶, and a starting key, E⁴⁰, which has absolutely no mechanical connection whatever with the keys, K, of Fig. 6. The operator sets up the numbers in this case the same as before, and then depresses the starting key, E⁴⁰. This latches, remaining down, in its operation severing the trunk

and closing the circuit of magnet E⁵ to the starting wire 84, just as before. When the starting impulse comes over wire 84, relay E⁵ pulls up and locks itself, also extinguishes the lamp L, closes the forward end of the trunk onto the sending wires 83, 86, and closes the stopping wire 85 onto the latch magnet, e⁴, of the key, E⁴⁰. The machine then makes a complete cycle, sending the impulses over the two sides of the trunk as before, and finally the stopping impulse comes over the wire 85 to the magnet, e⁴, which it positively energizes, tripping the key, E⁴⁰. The trunk is thus restored and the sending device is entirely cut off. In addition to the relay, E⁵, there is an extra relay, E⁶, which is merely of an intermediate character. It is energized by the pulling up of relay, E⁵, and controls restoring contacts in series with a back contact of the relay 1D, also controlling a direct battery connection to the locking wire 58. Passing now to the uppermost trunk in Fig. 5, I have therein shown the starting key E^k, held down by an electromagnet instead of a latch, this electromagnet taking its current from the wire 14 which is put on battery when the relay D' is energized. The operator sets up the numbers as before, and then positively depresses the starting key, E^k. This locks itself by its armature, e⁵, being gripped on the magnet, e⁶, closes the circuit of relay, E⁵, to the starting wire 84, and remains set. When the starting impulse comes over wire 84, the relay, E⁵, pulls up, the lamp, L, is cut off, the direct battery connection to wire 57 is cut off, the number wires 83 and 86 are put onto the back contacts of relay, E⁶, and the relay, E⁵, locks itself on the wire 14 controlled by relay, D'. The numbers then go in as before. The relay E⁵ also connects the relay E⁶ onto the stopping wire 85, and so when the stopping impulse comes the relay, E⁶, pulls up, completes the normally open trunk, and locks itself on the wire 14, at the same time positively cutting off all connection with the wires 83 and 86. In all these cases it will be observed that when the calling subscriber hangs up, and the tip relay, D, or 1D, or 2D falls back, battery is momentarily put on both sides of the trunk through the wires 23 and 24. The relay D falls back first, followed by the primary selector relays, which in turn cut off the relay, D', which in turn cuts off the wire 14 and the other relays. In the several arrangements I have devised and tried, I have considered it advisable to have these restoring impulses made positive. In fact, I consider this so far necessary, that in practice I shall provide an extra set of spring contacts on the operator's listening key, three in number, one being to battery and the other two connected to the two sides of the trunk, respectively. Thus whenever an operator cuts in

to get the number wanted, she will automatically restore the switches in advance of their use.

The arrangement shown in Fig. 5^a are still more positive than those previously described, employing the same principles. In the upper trunk of the figure starting relay, E⁴, is energized when any key, K^x, is depressed, which may be in the number set or separate. A circuit then is closed as follows: B, 7, K^x, E⁴ and ground. This relay pulls up, cutting off the positive battery connection from the locking wires 65, 51, putting the starting wire 84 through the wires 15 122 and 121 onto the relay E⁵, and locking itself through the wire 17 controlled by the relay D'. It also cuts off the lamp, L. When the starting impulse comes over the wire 84, it energizes relay E⁵, severing the 20 trunk circuit at its outer contacts, connecting the forward ends 30^x and 31^x to the number wires 83 and 86, and locking itself through the wire 85, which in this case is normally held continuous at the wheel, Q', 25 by a pair of closed springs going to battery through the wires 850 and 7. This wire 85 is the stopping wire, and when the pin, q^x, gets around to the springs, it opens them, causing the deenergization of the relay, E⁵, 30 which thereupon restores the trunk and cuts off the number wires. Between the first and second operations of the relay, E⁵, the relay, E⁶, pulls up, its circuit being closed when the relay, E⁵, first becomes energized. 35 The functions of the relay, E⁶, are to connect direct battery onto wire 123 for the release or clearing out impulses, and to disconnect the relay E⁵ from the starting wire 84. The relay, E⁶, locks itself through a 40 front contact of the relay, E⁴, which gets current direct from the battery. This direct battery connection is rather important, since it enables me to release these relays in 1, 2, 3 order, thus gaining a perceptible 45 time element for the release impulses. Suppose the switches have been set up, the called subscriber rung, and the conversation held. The subscribers hang up. Relay D lets go, and unlocks the primary relays, at the same 50 time connecting the wire 123 to both of the trunk wires 23 and 24. The release circuit may then be traced as follows: B, 7, armature of relay, E⁶, 123, 23 and 24 in parallel to 30^x and 31^x, simultaneously. It will be 55 observed that since this connection comes direct off of battery, it will stay on the trunk as long as the relay, E⁶, is energized. Now, the primary relays being cut off by the relay, D, they in turn cut off the relay, 60 D', and that in turn cuts off the relay, E⁴, which in turn cuts off the relay, E⁶, and this finally cuts off the wire 123, removing battery from the trunk. The time consumed in these successive steps is sufficient to give 65 the proper restoring impulses to positively

restore the switches. The relays in the other circuits I show herewith can be arranged in the same manner, so that the length of the restoring impulses can be regulated. In the arrangement at bottom 70 of Fig. 5^a, for instance, I show keys K^x, as before, which put battery on the relay, E⁴, this in turn connecting the starting wire 84 to the relay, E⁵, which puts the number wires 83 and 86 on the closed back contacts 75 of the relay E⁵, and so on the trunk ends; at the same time this relay, E⁵, connects the winding of the relay, E⁶, to the stepping wire 85. At the end of the cycle, relay E⁶ pulls up, completing the normally broken 80 trunk circuit, and cutting off the number wires. The relays of this trunk may be referred to as E⁵ signal starting relay, E⁶ signal stopping relay, and E⁴ manually operated relay auxiliary to the keys K^x. Each 85 of these relays locks in turn, and I cause the relay, D, to put battery onto the wires 23 and 24 the instant it lets go. This is followed by the primary relays letting go, the relay D' letting go, the relay E⁴ letting 90 go, the relay E⁵ letting go and finally relay E⁶ letting go. The last-named relay again breaks the trunk-circuit, of course disconnecting the wires 23 and 24 from the connector switches upon the extensions of 95 the wires 130^x-131^x.

I have already dwelt to some extent upon the arrangement of Figs. 13 and 14, hence I will not need to go into their operation again. I will say, however, that of all the 100 circuits presented herewith, I consider those in Fig. 5^a, when operated in connection with that of Fig. 6, to be the best, simplest and most positive. I have thus shown how the operator sets up the desired number, how 105 the same is started and put upon the trunk wires by the sending machine, and so to the switches. I will now briefly trace the operation of the switches as shown in Figs. 7 and 8, in response to these impulses. We 110 assumed the number 433-3. We also assumed that the switch S of Fig. 7 was either omitted or on a one thousand contact normally. Hence the group of four impulses that now come over the wire 30^x pass directly to the vertical relay, V, of the switch, S'. This works the magnet, v, to step up the spindle, s⁴, four steps, selecting the row containing the four hundred trunks. A single impulse follows over the wires 31^x 115 and 35, passing to the rotary relay, R, energizing the side switch magnet, U, which opens the vertical magnet circuit and throws the side switch one step. This cuts in the rotary magnet, r, and at the same time keeps 120 a test on so that the spindle turns until an idle or ungrounded trunk is found by the wiper, s⁸. The switch then stops. This brings us to a connector switch containing 125 terminals of lines from 400 to 499, includ- 130

sive. The next group of three impulses comes over the wires 30^x, 34, 36 and 38 to the vertical relay, V, in Fig. 8. This works the vertical magnet, v, to step up the spindle, s⁴, to the desired row, which is the third, containing the terminals of the line desired. A single rotary impulse follows over the wires 31^x, 35, 37 and 39 to the rotary relay, R, which closes the circuit of the side switch magnet, U, and throws the side switch-arms, u, all around one step. This cuts out the vertical magnet, v, cuts in the rotary magnet, r. Three more impulses follow over the vertical wire 38, which bring the wipers, s⁶, 15 s⁷ onto the third contact in this third row. We have now selected the line; it remains to test if it be busy, and to ring the wanted subscriber. A single rotary impulse comes along over the wire 39, again energizes the relay, R, which again in turn energizes the relay, U, and this again pulls up preparatory to throwing the side switch-arms the final step. In pulling up, however, it closes together the springs 140, thereby instantly 20 closing the following test circuit from the tip wiper, s⁶: 141, 4^u, 142, 140, 143, T, 144, 67, and battery to ground. Now, if the line wanted be busy, either because of its calling or being called, there will be a ground on 25 its tip side contacts, either through the relay, X, of a connector switch, or the relay D of a trunk. These are comparatively low resistance relays, and the test relay, T, is wound so as to be quite sensitive. If this 30 ground is found, therefore, at the instant of testing, the relay, T, pulls up, closing the circuit of the release magnet, t, and the switches all return to zero position. On the other hand, if no ground is found, the 35 switch is not released, but the relay U makes its second movement after the rotary impulse ceases, and the side-switch-arms all move to their third position, thus completing the circuits: 38—40—42 and 39—41—430 for 40 conversation. There are still three impulses to come over the line for selective signaling purposes. These come in over the wire 38, work the vertical relay, V, and put three 45 impulses on the wire 47. Since the switch-arms 1^u, 2^u, etc., are now in their final positions, the wire 47 has become connected to the wire 48, leading to the relays w', w². Hence these three impulses work the selective set, W, in the following manner: The 50 first impulse pulls up the relay w' and also the solenoid, w². The solenoid breaks the commutator circuit 119 or the generator circuit 106—109, or both; these remaining broken as long as the impulses are coming, 55 and being restored as soon as they cease. The relay, w', puts battery on wire 68, and then as it falls back on wire 69, and so back and forth until it has set all the relays in the combination, W, thereby cutting in the 60 last generator, G³. No rotary impulse fol- 65

lows this; but it would be idle if it did, producing no effect. The cessation of the impulses permits the solenoid, w², to return fully, and the commutator, Y, thereupon proceeds to work the ringing relay, w, in 70 the predetermined manner.

In selecting the last generator, G³, we assume that the ringer at the station, A³, on the line selected will respond to that current. This being so, the subscriber gets the signal, 75 and in due time answers. If he takes down his receiver in the middle of a ringing impulse, the alternating current will continue to flow over the line until the commutator Y has taken it off; but when so taken off, by 80 the temporary deenergization of the relay, w, battery current at once flows out to the subscriber's line and back to central through the two relays X, X' as follows: B, 67, X', 105, 41, 430, 90, line wire, A³, return line 85 wire, 70, 42, 40, 104, X, ground and back to battery. The relay, X', had already pulled up when final connection was effected with the line, current then flowing through w' 105, 41, 430, 90, to the cut-off relay, M' 90 and ground; but the tip relay X now also pulls up, at once disconnecting the ringing relay, w, from the battery wire 102, and also connecting said battery wire through wire 103 to the locking relay, w³. The actual disconnection of the wire 101 by the relay, X, 95 is of course duplication of what follows, but in dealing with ringing currents, duplication is error on the safe side. The relay, w³, 100 pulls up, disconnects the commutator from the relay, w, and locks itself through the battery wires 67, 102 subject to the control of the relay, X'. These conditions continue throughout the conversation.

By preference I give control of the connection to the calling subscriber. I can, however, arrange the relays, X and w³ so that they will control the release magnet, t, when the called subscriber hangs up. This will be required in some cases, as otherwise 105 a man could be called and his line "hung up" so as to be useless for an indefinite period. In addition, however, the calling subscriber and the answering operator should always have control. When this subscriber hangs up, his relay, D, in Fig. 5, 5^u, or 14 lets go, connecting battery to both sides of the trunk simultaneously. These simultaneous impulses getting on the wires 38 and 39 in Fig. 8 energizes both relays V 110 and R simultaneously, whereupon a release circuit is closed as follows: B, 67, 144, T, 145, 146, through the wiper s⁸ in Fig. 7; 147, T, 148, 4^u, 149 and ground. The two relays, T, pull up, closing the circuits of 115 their release magnets, t, that in Fig. 8 being direct to ground from the wire 67, and that in Fig. 7 going by the following path: B, 150, t, 151, 152, s⁸, 153, T, 154, 4^u, 155, ground. All the switches are thus restored 120 130

in turn. The deenergization of relay, D, in Fig. 5, also takes battery off of the locking wire 57, hence the two relays which are holding the calling line on the trunk let go 5 their armatures, the trunk becomes disconnected from the line, the cut-off relay of the line loses current and puts it back on its line relay, and the relay, D', of the trunk loses current, thereby cutting off all the other 10 trunk relays and restoring the entire apparatus to its normal inactive condition. It will be understood that in speaking of the relay, D, or D' and the like, I mean by this any of the tip or sleeve relays in the respective trunks, without regard to their coefficients.

Having thus described my invention, I wish to state that there are a great many changes that can be made, without departing 20 from the underlying principles of my invention. I consider myself to be the first inventor of any system in which the operator receives the calls direct on her connective circuit, and merely sets up the number wanted; also, the first inventor of a system employing a separately driven 25 sender or senders for operators, that is a sender requiring no power to be communicated by the operator. I shall claim these 30 and all the other features presented both broadly and specifically, and I desire the language of my claims to be given the broadest and most liberal construction.

In addition to the use of the primary 35 selectors for the purpose of answering calls and getting them onto idle trunks, I also use what I may call secondary selectors for the purpose of decreasing the number of operators' equipments and keyboards. Take 40 the example of an exchange equipped as I have hereinbefore described it, serving 6,000 subscribers' lines, and assume that during the busy hours there is an average of one call per line or a total of 6,000 in the exchange. It will be observed that the operators in my system have only to press a 45 button to get the number, and to press other buttons to set up the same number. The operation of setting up the number by touching the proper buttons is sub-consciously controlled after sufficient practice has been had, as in any other case of purely manual dexterity, such as typewriting. By actual trial the time consumed in receiving and setting up a number having five digits, averages about 2.9 seconds. A very little figuring will suffice to show that on a three second basis the operator could handle twenty 55 calls per minute, or twelve hundred per hour. Taking one-half this, I fix six hundred calls per hour as a standard maximum, and I furnish the operators with sufficient apparatus for this and no more. In the arrangement heretofore described, there is one 60 complete set of buttons, with its connec-

tions, for each trunk. Instead of having such a complete set of buttons K, as shown in Fig. 6, for each trunk, the preferable method in practice is to provide only a sufficient number of sets to handle the business, 70 and connect them to the trunks by secondary selectors, similar to the primary selector sets of relays which I have heretofore described. Each secondary selector set takes care of one hundred terminals, or one hundred trunks can thereby make connection with that operator. Every additional secondary selector gives the operator facilities for reaching an additional one hundred trunks. In the case of a six thousand line 80 exchange assumed above, there are six hundred trunks, and twelve operators. By preference each operator would have six sender devices, terminating in six secondary selectors, each containing the terminals of one 85 hundred trunks. The main trunks being divided into six groups of one hundred each, the first one hundred would be multiplied into the secondary selector relay contacts of the No. 1 senders of all the twelve girls. 90 The second group of main trunks would be similarly multiplied to the No. 2 secondary selectors of all the twelve girls; and so on, each main trunk thus having twelve multiples by which to gain the attention of 95 an idle operator. In operating these secondary selectors, Figs. 2, 3, 4 and 12 are followed.

Fig. 15 shows the coöperating circuits, with the operator's set and starting key 100 taken away from the trunk. When a calling line has been put upon a main trunk by a primary selector, the sleeve relay D' of that trunk pulls up and closes the branches 350-351, from battery B to the tens and 105 units relays ON and OP respectively of the first idle operator's trunk, and thence through the contacts of a cut-off relay D^{xx}, corresponding to the relays D^x, etc., of the trunks. The relays ON and OP pull up and 110 lock on the circuit 352-353-354-355-D¹⁰, 357, 358, extending from ground to the main battery B through a back contact on the last relay E⁴⁰⁰ in the sending set (which is operated when the stopping impulse comes) 115 after the signal has been sent. The operator comes in as already described, with her push button, gets the number wanted, sets the same up on the particular bank of keys over which the signal lamp L has been lighted 120 (this lamp also being controlled through the relay D¹⁰, included in the locking circuit 354, etc., at the cutting on and cutting off of the secondary selector relays); then presses the starting button in Fig. 15 and turns to 125 other business. The starting button closes the circuit of the starting relay E⁵⁰, and when the starting impulse comes over the starting wire 84, relay E⁵⁰ pulls up, putting the number wires 83 and 86 on the operator's branch 130

trunk wires 383 and 386 respectively and so on to the main trunk wires 30-31, and to the switches. The starting relay E^{50} also connects the stopping relay E^{400} , to the stopping wire 85, and when the final impulse comes over that wire this relay pulls up, thereby breaking the locking circuit 358-7-6-5-4-3-2, of the operator's secondary selector relays, and cutting the operator's set entirely off the main trunk. This leaves the trunk clean and clear from one subscriber to the other, with the additional advantage that it is absolutely physically impossible for the operator to get back on either trunk or the lines, this being accomplished in the same manner as in Fig. 5, by the locking up of relay E^6 in Fig. 5, and prevents the operator being called a second time during the use of a trunk. The other connections in Fig. 15 will be readily understood by comparing it with Figs. 5, 5^b and 6, as it is identical in substance, embodying only such modifications as are necessary to separate the operator from the trunk.

With an arrangement such as just mentioned, employing secondary selector circuits, the number of operator's keyboards becomes so small that in order to avoid possible confusion it is sometimes advisable to have a separate set of sending wheels, Q, Q', etc., or their equivalent drums, for each operator. These separate drums or sets of wheels are preferably driven by the same shaft and staggered with regard to each other so that their starting impulses will follow in succession. The reason for this is that if two operators should set up the same number at the same instant, one of the trunks would slightly precede the other in connecting with the line wanted, so that the second test would find the line "busy." This arrangement is not essential, and it comprises a mere multiplication of the circuits of Figs. 6 or 13, but it is covered by the scope of my claims, which I shall direct in part to the idea of power-driven sending machines broadly.

It is to be observed that a very important feature of the system I have hereinbefore described lies in its adaptability to service conditions in exchanges consisting of a plurality of central offices. In manual practice the setting up of connections between subscribers in different exchange offices is by trunking, between operators known as the "A" and the "B" operators, respectively. The A operator is the subscriber's operator, who takes the call and initiates the connection. If in her own office she completes it through the multiple in the usual way. If in another office, she gets on an order wire to the other exchange and gets the attention of a B operator thereat. Sometimes she has to wait for the B operator, and this causes delays which are hard to explain to the ordinary telephone user.

After getting attention, an idle trunk is named, the A girl goes in on that trunk, the B girl does the same, and the latter takes the trunk plug and inserts it in the wanted line-jack. The A girl then does the ringing by means of relays manually controlled, and supervises. If selective ringing is to be done, the B girl must set the keys.

In the present system all the undesirable features of this trunking operation are avoided. In the first place there are no B girls, the A girl setting up the buttons of her sender for trunking calls the same as for those in her own office. If the different offices are not too large the numbers may be run consecutively. Thus the main office may have numbers from 1 to 5000, the north from 5000 to 7000; each from 7000 to 8000, and so on. Or, as in the present manual classification, the offices may have designations such as I have prefixed in the foregoing, and these may have a prefix set of buttons which will send a preliminary set of impulses in the originating office. The trunks from office to office may be either between the first and second selectors, or before the first selector. The first set of switches to be reached in a trunk call takes the place of a B girl, and the ringing being selective in any case can be controlled between exchanges as well as in one office. For long-distance or toll or other special calls manual boards may be provided and terminals assigned them on the connector banks or perhaps in the selector banks. Thus long distance may be 6000, for instance, which would put the first selector switch on the sixth row of trunks and cause it to select an idle one to the long distance board, where it would light a lamp as usual.

It will be apparent from a little study that many conditions can be met with the system which have heretofore been difficult to handle. Thus take the case of a subscriber who has changed his number. Until a new directory is issued, and even afterward, the old number will be called. Such a changed line should be "monitored", that is handled on the monitor's desk for at least a short while. In my case I simply take wires from the terminals of both the old and the new numbers to the monitor's board, and calls are then handled there manually, both pairs terminating preferably in jacks. A still simpler solution would be to actually tie the terminals together on the connector switches by means of jumper wires for a while; but this cannot be done where the old number is assigned to a new subscriber. Take another case. A party line subscriber wants to keep his old number but has moved to another part of town, or may be willing to sacrifice his old number but desires to save the calls. In this case I provide a re-

lay or signal responsive to the particular frequency of current which would ring the bell at the station of the subscriber in question, and cause this relay to act whenever his old number is called, landing the call on the monitor's desk as before, the old and new lines thus being both available. Of course in such case the monitor simply tells the caller to call again, giving the new number. The monitor's desk takes the place of one station on the line. Still another case. It often happens in automatic systems that a line will be called by malicious parties from some outside point, and either silence follows the answer to the call, or perhaps an obscene or profane remark. Heretofore it has been difficult or impossible to ascertain the guilty party or the station from which the call came. In the present system I handle such cases with others by means of a "detective" desk. Any line needing protection or watching is connected to a jack on this desk, either as a terminal or by merely looping the jack on the line. Every call from or for the line then manifests itself to the detective operator, who is usually a stenographer as well. It will be noted in the switch diagrams that the release is back from connector to selector, etc. When the connector release circuit is opened of course it prevents the operation of the other release magnets. I particularly point out the fact that in none of this special work is the A operator the least bit diverted from her regular work, which is to take numbers and set them up. She does not know where the connections go, nor care. Her duty is done when she has pushed the right buttons.

The foregoing are included in the scheme of my system, and the grouping of stations in branch exchange groups, as well. Many other matters also will occur to the contemplative mind on reading the specification with care, which may not be specifically illustrated or described in this application, yet which clearly would fall within the spirit and scope of my invention.

I do not herein claim broadly tri-headed trunks or secondary distribution of calls to operators, inasmuch as the same are claimed broadly in the following copending applications of mine, Serial Nos. 369,201, filed April 20, 1907; 383,874, filed July 15, 1907; and 383,875, filed July 15, 1907.

Having thus described my invention what I claim and desire to secure by Letters Patent is:—

1. In a telephone exchange system a plurality of subscribers' lines, a central station and automatic switches thereat less than the number of lines, means actuated in response to a call over a line to connect the same with an automatic switching circuit, and means controlled by an operator to actuate

the switch or switches so as to effect the desired connection, and consisting of a bank of selecting push buttons and a set of continuously revolving associated commutator devices. 70

2. In a telephone exchange system a plurality of subscribers' lines with a central office for the same and automatic switching devices in said central office less in number than the number of lines, means automatically actuated in response to a subscriber's call to connect his line with idle automatic switching devices, and means controlled by an operator for thereafter actuating said switches to connect the calling line as desired, and consisting of a bank of selecting push buttons and a set of continuously revolving associated commutator devices. 75

3. In a telephone exchange system a plurality of subscribers' lines, a central office therefor, automatic switching devices at said central office less in number than the number of lines, an automatic primary selector adapted to connect a calling line with idle switching apparatus, in response to the subscriber's call, a signal adapted to be displayed by the line so calling, and means whereby an operator may effect connection with the calling line to obtain the number wanted, and further means comprising constantly driven signal-impulse commutators and a bank of impulse selecting push buttons whereby the operator may set the automatic switching apparatus with which the calling line is connected so as to select and connect with the line wanted. 90

4. In a telephone exchange system, a central office equipment comprising incoming line-terminals, a number of automatic switch sets less in number than the number of lines, automatic primary selectors for connecting calling lines to idle switch sets, a multiple signal impulse transmitter, and operators' keys for selectively connecting said transmitter to the switches. 105

5. In a telephone exchange system a plurality of subscribers' lines, a number of automatic switching devices less than the number of lines, automatic primary selectors responding to calls and acting to connect the calling lines with idle switches, relays for the selectors and switches controlled by the calling subscriber, a common multiple signal transmitter, and operators' keys for connecting the same selectively, together with automatic means to break said connection when the switches have been actuated. 115

6. In a telephone system, a plurality of line circuits, a plurality of trunks, means for connecting said trunks to calling telephone lines, electromagnets associated with each trunk for controlling said means, relays associated with the trunks, a source of current, and connections from said source of current through contacts of said relays. 125

- to the controlling magnets so as to be exclusively controlled by said relays, which act when energized to interrupt the connection from said source of current to a busy 5 trunk, and to complete the connection from said source to the next idle trunk, substantially as described.
7. In a telephone system, lines; a group of trunks less in number than the number of 10 lines, means for connecting each of said trunks to a calling one of said lines, operating electromagnets controlling said means, a source of current, circuits extending therefrom to the respective trunks, and electromagnetic switching means associated with the respective trunks and becoming active as the latter become busy, and exclusively controlling said circuits, whereby said source of current is connected to the operating magnet 15 of one idle trunk of said group and whereby said source of current is disconnected from the operating magnets of all other trunks of said group, substantially as described.
- 20 8. In a telephone system, a group of lines; a group of trunk relays, associated with said trunks and adapted to connect said trunks to a calling telephone line; operating electromagnets controlling the circuits of 25 said trunk relays, a source of current, a pilot relay associated with each trunk and energized when the trunk is in use and deenergized when the trunk is not in use; a controlling circuit from said source of current 30 to the operating magnet of its trunk, whereby current is removed from the operating winding of the operating magnet when said trunk is connected with a calling line; a serial circuit associated with the armature 35 of said pilot relay, whereby when first trunk is busy the source of potential is passed to the pilot relay of the second trunk of the group, and when said first and second trunks are busy, the source of potential is connected 40 to the pilot relay of the third trunk of said group, and so on throughout the group, substantially as described.
- 45 9. In a telephone system, a group of lines, a group of trunks less in number than the 50 number of lines; switching devices adapted to connect any of said trunks to a calling one of said lines, a battery, operating magnets associated one with each trunk for controlling said switching devices, a battery-controlling relay pertaining to the first of 55 said trunks and having its contacts in the path between the battery and the operating magnets of its trunk, and having said contacts closed when it is deenergized; and a 60 pilot relay associated with said trunk and energizing said battery controlling relay when said trunk is busy, and closing a circuit from battery to the pilot and battery-control relays of the second trunk of said 65 group when said first trunk is connected with a calling line; substantially as described.
10. In a telephone exchange system, a plurality of subscribers' lines; a central station and automatic switches thereat less than the 70 number of lines; means actuated in response to a call over a line to connect the same with an automatic switching circuit; and means controlled by an operator to actuate the switch or switches so as to effect the desired 75 connection, and consisting of a bank of selecting-push buttons and a set of revolving associated commutator devices, substantially as described.
11. In a telephone exchange system, a plurality of subscribers' lines; a central station and automatic switches thereat less than the 80 number of lines; means actuated in response to a call over a line to connect the same with an automatic switching circuit; and means controlled by an operator to actuate the switch or switches so as to effect the desired 85 connection, comprising a set of continuously revolving associated commutator devices, substantially as described.
- 90 12. In a telephone exchange system, a plurality of subscribers' lines with a central office for the same and automatic switching devices in said central office less in number than the number of lines; means automatically actuated in response to a subscriber's call to connect his line with the idle automatic switching devices; and means controlled by an operator for thereafter actuating 95 said switches to connect the calling line as desired, and consisting of a bank of selecting push buttons and a set of associated commutator devices, substantially as described.
13. In a telephone exchange system, a plurality of subscribers' lines, a central office, automatic switching devices, means automatically actuated in response to a subscriber's call to connect his line with idle automatic switching devices; and means controlled by an operator for thereafter actuating 100 said switches to connect the calling line as desired, and consisting of a bank of selecting devices and a set of continuously revolving associated commutator devices, substantially as described.
- 105 14. In a telephone exchange system, a plurality of subscribers' lines with a central office for the same and automatic switching devices in said central office less in number 110 than the number of lines; means automatically actuated in response to a subscriber's call to connect his line with idle automatic switching devices; and means controlled by an operator for thereafter actuating 115 said switches to connect the calling line as desired, and consisting of a bank of selecting devices and a set of associated commutator devices, substantially as described.
15. In a telephone exchange system, a plu- 120

rality of subscribers' lines; a central office therefor; automatic switching devices at said central office less in number than the number of lines; an automatic primary selector adapted to connect a calling line with idle switching apparatus in response to the subscriber's call; a signal adapted to be displayed by the line so calling; and means whereby an operator may effect connection with the calling line to obtain the number wanted; and further means comprising signal impulse commutators and a bank of impulse selecting push buttons whereby the operator may set the automatic switching apparatus with which the calling line is connected so as to select and connect with the line wanted, substantially as described.

16. In a telephone exchange system, a plurality of subscribers' lines; a central office therefor; automatic switching devices at said central office less in number than the number of lines; an automatic primary selector adapted to connect a calling line with idle switching apparatus in response to the subscriber's call; a signal adapted to be displayed by the line so calling; and means whereby an operator may effect connection with the calling line to obtain the number wanted; and further means comprising signal impulse commutators and impulse selecting devices whereby the operator may set the automatic switching apparatus with which the calling line is connected so as to select and connect with the line wanted, substantially as described.

17. In a telephone exchange system, a plurality of subscribers' lines; a central station and automatic switches therewith less than the number of lines; means actuated in response to a call over a line to connect the same with an automatic switching circuit; and means controlled by an operator to actuate the switch or switches so as to effect the desired connection, and consisting of a bank of selecting keys and a set of associated commutator devices, substantially as described.

18. In a semi-automatic telephone exchange system, line circuits, link circuits for interconnecting the lines, primary switching means responsive to calls over the lines for connecting calling lines to idle links, impulse actuated automatic switching mechanism for connecting said links to the wanted lines, an operator's equipment including a telephone and a selective impulse sender, means to connect said equipment to a link, and a cut-off relay in each link controlled from the operator's equipment, and adapted to sever the link during the transmission of impulses to the automatic switching mechanism, whereby the calling party is prevented from hearing the impulses used to actuate

the automatic switching mechanism in the selection of the wanted line, substantially as described.

65

19. In a semi-automatic telephone exchange system, line circuits, link circuits for interconnecting the same, primary selector switching mechanism for each link circuit, containing terminals of the lines and responsive to calls thereover to connect a calling line to an idle link, automatic driven switches associated with the said links, and adapted to receive impulses therethrough to connect the links to wanted lines, a sending machine for supplying impulses to the switches, an operator's key set for determining the order and arrangement of said impulses, means to connect said key set and sending machine to a link, a starting relay initially energized by the use of an operator's key, and a cut-off relay in the link, having its circuit closed when said starting relay is energized, and acting to sever the link conductors and connect the forward or switch ends thereof to impulse wires leading to the key set and sending machine, and leaving the other conductors open whereby the calling party is prevented from hearing the impulses that are used to drive the connecting switches to the wanted line.

70

20. In a telephone exchange system, a plurality of lines to be inter-connected, a plurality of automatic switches for effecting the inter-connection, but normally disconnected from said lines, automatic means for connecting the switches to calling lines, and an operator's sender for controlling said automatic switches, said sender comprising a key-board having keys or buttons arranged in groups corresponding to the digits of the numbers to be called, and means to connect said sender to any of said automatic switches.

80

21. In a telephone exchange system, a plurality of lines to be inter-connected, a plurality of automatic switches for effecting the inter-connection, but normally disconnected from said lines, means controlled by the receiver hooks at the subscribers' instruments for connecting the said switches to calling lines, and an operator's sender for controlling said automatic switches, said sender comprising a key-board having keys or buttons arranged in groups corresponding to the digits of the number to be called, and means to connect said sender to any of said automatic switches.

85

In testimony whereof I affix my signature in presence of two witnesses.

EDWARD E. CLEMENT.
